[57] CLAIM

The ornamental design for a lawn sprinkler, as shown and described.

DESCRIPTION

FIG. 1 is a perspective view of a lawn sprinkler showing my new design;

FIG. 2 is a top plan view thereof;

FIG. 3 is a rear elevational view thereof;

FIG. 4 is a bottom plan view thereof;

FIG. 5 is a front elevational view thereof; and

FIG. 6 is an elevational view taken from one side thereof, the opposite side being a mirror image of the side shown.

FIG. 1

FIG. 2

FIG. 5

FIG. 3

FIG. 6

FIG. 4
